UNITED STATES PATENT OFFICE.

JAMES F. McELROY, OF ALBANY, NEW YORK, ASSIGNOR TO CONSOLIDATED CAR HEATING COMPANY, OF ALBANY, NEW YORK, A CORPORATION OF WEST VIRGINIA.

ENGINEER'S VALVE.

No. 821,818.

Specification of Letters Patent.

Patented May 29, 1906.

Application filed October 23, 1905. Serial No. 283,918.

To all whom it may concern:

Be it known that I, JAMES F. McELROY, a citizen of the United States, residing at Albany, in the county of Albany and State of New York, have invented certain new and useful Improvements in Engineers' Valves, of which the following specification and accompanying drawings illustrate the invention in a form which I now regard as the best out of the various forms in which it may be embodied.

This invention relates to an engineer's valve for air-brake systems, and is especially adapted to the system described in my Patents Nos. 768,537 and 768,538, although not restricted to such use. It is an improvement upon the form of valve described in my Patent No. 792,152, of June 13, 1905, wherein are shown inlet and exhaust valves for the train-pipe operated by a motor-piston whose cylinder-pressure is increased or decreased by means of relay-valves, which themselves are controlled by a diaphragm having on one side the train-pipe pressure and on the other side the pressure of the atmosphere and of a spring whose tension is regulated manually by the engineer.

My present object is to simplify this mechanism, reduce its cost, increase its durability, and secure various constructive and operative advantages. The main inlet and exhaust valves are accordingly attached to separate motor-pistons which permit some leakage past them into their cylinder-chambers, whose outlets are under control of the relay-valves. The latter, two in number, are seated oppositely by movement of the diaphragm and serve to control only the exhaust from the motor-piston chambers. Formerly the single motor-piston had a neutral position and was moved to either side of this position to open either the inlet or exhaust valve of the train-pipe, whereas now the intermediate neutral position is dispensed with, the motor-pistons are not subject to such great differences of pressure, require less power to operate, and need not be packed. These advantages are accompanied by greater simplicity in the relay-valves and a more compact and accessible arrangement

of parts consequent upon their novel mode of construction.

Of the accompanying drawings, Figure 1 represents a vertical side section of a commercial form of my invention. Fig. 2 represents a vertical middle section thereof. Fig. 3 represents a plan view of the lower casing. Fig. 4 represents a diagrammatic or developed sectional view with some parts out of actual relative positions with the object of clearly showing the arrangement, some features of construction—as, for instance, the means of removing pistons—being omitted.

The same reference characters represent the same parts in all the views.

Referring to Fig. 4, 10 indicates a casing having chambers 11 12 13, adapted to be connected, respectively, with the train-pipe, the main reservoir, and the exhaust, and 14 15 are valves controlling, respectively, the inlet from the reservoir to the train-pipe and the exhaust from the train-pipe to the atmosphere. These valves are attached to pistons 16 17, having an easy fit in cylinders 18 19, so as to permit leakage from their front to their rear sides into the cylinder-chambers 20 21. These chambers connect by ports 22 23 with two valve-chambers 24 25, the outlets of which lead, respectively, to the diaphragm-chamber 26, connecting with the train-pipe, and to the atmosphere and are controlled by the relay-valves 27 28, the forming seating upwardly and the latter downwardly by means of springs 29 30. The main valves 14 15 are seated by springs 31 32 when the pressures equalize on opposite sides of their pistons.

33 is a diaphragm receiving on its lower side the train-pipe pressure and on its upper side the pressure of a spring 34, whose tension is varied by adjusting the nut 35, to which is attached the engineer's handle, substantially as in my Patent No. 792,152.

Under the diaphragm 33 is a follower 36, raised by a light spring 37 and having a ledge 38, which takes under a flange 39 on the stem of relay-valve 28, so as to lift said valve. Downward movement of the diaphragm may take place after the valve 28 is seated, and this movement opens the other relay-valve 100

27 by means of a stem 40 on the latter, engaged by the edge of the follower 36. In the operation of this mechanism the train-pipe pressure to be maintained is determined by 5 the set of the nut 35, which establishes a certain tension in the spring 34. If the train-pipe pressure in chamber 26 below the diaphragm is unsufficient to balance the spring-pressure, the diaphragm falls and opens re-
10 lay-valve 27. Thereupon the pressure in cylinder-chamber 20, which had become equal to reservoir-pressure by venting or leakage past the piston 16 and had permitted the valve 14 to be seated by its spring 31, is now
15 exhausted to the train-pipe pressure in chamber 26, which is always lower than that of the reservoir, and the main inlet-valve 14 opens and admits reservoir-air to the train-pipe. When train-pipe pressure is restored to the
20 pressure of spring 34, the relay-valve 27 closes, and the leakage past piston 16 will then quickly restore valve 14 to its seat. If train-pipe pressure is above the pressure of spring 34, diaphragm 33 rises and opens the
25 other relay-valve 28, which exhausts the leakage air from chamber 21 to the atmosphere and permits the train-pipe pressure acting against piston 17 to open the main exhaust-valve 15 and decrease the train-pipe pressure.
30 Thus train-pipe pressure is automatically maintained at the standard determined by the set of the engineer's handle. This standard may at any time be varied by manually altering the tension of spring 34 with a new
35 set of the handle for the purpose of increasing or decreasing the pressure of the brakes or releasing them.

Figs. 1 to 3 show a form which my invention preferably assumes in commercial use.
40 The principle is the same as in Fig. 4 and the passages, ports, and chambers have substantially the same connections and are represented by the same reference characters. The piston-cylinders are horizontally placed and provided with removable heads or screw-caps 41, whereby the pistons and main valves may be reached. The relay-valves 27 28 may also be reached by the removal of screw-plugs 42 43, one of which is a valve-
45 stem guide and the other a guide and valve-cage.

What I claim as new, and desire to secure by Letters Patent, is—

1. An engineer's valve mechanism comprising separate and independently-movable valves controlling respectively the inlet to and exhaust from the train-pipe and each having a piston working in a cylinder and adapted to permit leakage past it into the cylinder-chamber 55 behind the piston, springs for closing said valves, means for establishing the main reservoir-pressure and the train-pipe pressure respectively on the front sides of the pistons, oppositely-opening relay-valves controlling the

exhaust from the respective cylinder-chambers, a movable partition for operating said relay-valves, having on one side of it the train-pipe pressure, a spring pressing on the opposite side of said partition, and means for manually varying the tension of said spring. 65

2. An engineer's valve mechanism comprising primary means for admitting air to and exhausting it from the train-pipe to release and set the brakes, leakage piston mechanism controlling said means and operated in one direction by air-pressure and in the other direction by spring-pressure, and relay-valve mechanism for exhausting the leakage air and permitting the air-pressure to operate said means. 70

3. An engineer's valve mechanism comprising a train-pipe, independently-movable normally closing inlet and exhaust valves therefor, cylinders for the respective valves, pistons attached to the valves and having a leaking fit in said cylinders, and alternately-opening relay-valves controlling the exhaust of leakage air from said cylinders. 80

4. An engineer's valve mechanism comprising inlet and outlet valves controlling the train-pipe pressure, means for opening said valves by the pressure of the main reservoir and the train-pipe respectively, means for venting the air which operates the valves to permit their closure, and alternately-operating valves for exhausting the vented air to cause the opening of the train-pipe valves. 90

5. An engineer's valve comprising inlet and outlet valves controlling train-pipe pressure and opened by reservoir and train-pipe pressure respectively, means for venting the valve-operating air to permit closure of the valves, and means subject differentially to train-pipe pressure and a manually-adjustable pressure for alternately exhausting the bodies of vented air. 100

6. An engineer's valve mechanism comprising two cylinders open respectively at one end to the main reservoir and to the train-pipe, oppositely-opening relay-valves for exhausting the other ends of said cylinders, a common operating mechanism for said valves, loose-fitting pistons in said cylinders having valves controlling the inlet and exhaust of the train-pipe respectively, and springs tending to move the pistons to valve-closing position. 110

7. An engineer's valve mechanism comprising primary means for charging and discharging the train-pipe to release and set the brakes, said means including a cylinder, a leaking piston therein having a primary valve controlling the train-pipe air and opened by air-pressure on the piston, means exerting a constant valve-closing pressure, a relay-valve for exhausting the leakage air, a movable partition for operating said relay-valve having train-pipe pressure on one side 120

thereof, a spring pressing on the opposite side of said partition, and an engineer's manual adjuster for varying the tension of said spring and producing the operation of said primary means.

5 8. An engineer's valve mechanism comprising a cylinder, a leaking piston therein having a valve controlling the exhaust of the train-pipe and opened by train-pipe pressure, a spring for closing said valve, and a relay-

valve for exhausting that end of said cylinder containing the leakage air.

In testimony whereof I have hereunto set my hand, in the presence of two subscribing witnesses, the 17th day of October, 1905.

JAMES F. McELROY.
